UNITED STATES PATENT OFFICE.

WALTER McGEE, OF PAISLEY, AND ANDREW DONALD, OF GLASGOW,
SCOTLAND.

LOOM FOR WEAVING WIRE-CLOTH.

SPECIFICATION forming part of Letters Patent No. 761,984, dated June 7, 1904.

Application filed August 18, 1903. Serial No. 169,315. (No model.)

To all whom it may concern:

Be it known that we, WALTER McGEE, residing at Laighpark, Paisley, Renfrewshire, and ANDREW DONALD, residing at 395 Eglington street, Glasgow, Scotland, subjects of the King of the United Kingdom of Great Britain and Ireland, have invented certain new and useful Improvements in Looms for Weaving Wire-Cloth, of which the following is a specification.

This invention, which relates to looms for weaving wire-cloth, has for its object to simplify and improve the construction and operation of such looms, and more especially to provide improved means for operating the lathe so that a double knocking or beating up of the wire weft is mechanically obtained, akin to that practiced in hand-loom weaving of wire-cloth, while maintaining a high speed of the loom and greatly increasing the production.

The invention is illustrated in the accompanying drawing, the figure of which is an end elevation of the framework of a loom, showing the improvements attached thereto.

For the purpose of knocking up the wire weft while the warp-shed is open, so that the weft may the more readily assume the sinuous form due to interweaving with the warp led from the warp-beam K and again beating it up to the fell when the shed is closed, the lathe *a*, pivoted at *a'*, is operated by toggle links or levers *b b'* and a connecting rod or link *c* on a single-throw crank *d*. The toggle-link *b* is jointed to the lathe and the link *b'* to the stationary loom-frame *e*, while the connecting-rod *c* is jointed to the meeting ends of both links *b b'* in such wise that when the toggle-links are in line, and preferably in horizontal position, the lathe is at the end of its stroke of beating up the wire to the fell, but when the links *b b'* are out of line under or over the center the lathe *a* is drawn back. When the toggle-links *b b'* are at their lowest point under the center line through the joints, the lathe *a* is fully back, as shown in dotted lines at A, and the weft-shot is thrown either by shuttle or by threading-needles, the crank *d* being at the lowest point of its throw, and as the crank *d* turns and through the connect-

ing-rod *c* raises the toggle-links *b b'* into line 50 the first knocking or beating up of the wire occurs. In the position showing the lathe *a* in full lines the links *b b'* are approximately horizontal, the lathe *a* having just completed its stroke. The links *b b'* are carried above or 55 beyond the center line by the further rise of the crank *d* to draw back the lathe to the position shown in dotted lines at B, and as the crank *d* passes the dead-point and returns on the downward movement the links *b b'* are 60 again brought to and past the center line to effect the second forward beating-up and return movements of the lathe, both knocking or beating-up movements being effected in a single revolution of the crank *d*. The crank-shaft *f* has imparted to it a varying speed of 65 rotation at each throw in order that when going forward to give each beating-up blow the lathe may travel rapidly, and on the final return movement it may move slowly or have 70 a slight dwell to allow time for the weft-shuttle to go through the shed. For this purpose the crank-shaft is driven by elliptical gear-wheels *g g'* or by equivalent gear from the motion-shaft *h*.

In further respects the loom may be of the usual type having let-off and take-up motions to insure greater regularity in weaving the cloth.

Having now described our invention, what 80 we claim, and desire to secure by Letters Patent of the United States, is—

In a loom for weaving wire-cloth, in combination with a lathe *a* pivoted at *a'* to the loom-frame *e*, a pair of toggle-links *b, b'* the 85 toggle-link *b* being jointed at one end to the lathe, and the toggle-link *b'* being jointed at one end to the loom-frame *e*, a connecting-rod *c* to which is jointed the other ends where these meet, of said toggle-links *b, b'* the connection being such that when the toggle-links *b, b'* are in line in horizontal position the lathe is at the end of its stroke of beating the wire up to the fell, but when the toggle-links are out of line under or over the center the lathe 95 is drawn back, a single-throw crank *d* to which said connecting-rod *c* is connected, the toggle-levers being brought into line twice

for each rotation of the crank, a crank-shaft f to which said crank d is secured, the motion-shaft h and elliptical gear-wheels g, g' , transmitting variable motion to said crank-shaft f ,
5 so as to impart differential velocity to the lathe in its swinging forward and return movements as shown and described.

In testimony whereof we have signed our

names to this specification in the presence of two subscribing witnesses.

WALTER McGEE.
ANDREW DONALD.
